UNITED STATES PATENT OFFICE

117,808

DESIGN FOR A PORTABLE ALTAR

Rudolph T. Gudell, North Chicago, Ill., assignor of one-half to George A. Feeny, Chicago, Ill.

Application September 5, 1939, Serial No. 87,052

Term of patent 3½ years

To all whom it may concern:

Be it known that I, Rudolph T. Gudell, a citizen of the United States and a resident of North Chicago, in the county of Lake and State of Illinois, have invented a new, original, and ornamental Design for a Portable Altar, of which the following is a specification, reference being had to the accompanying drawing, forming a part thereof, and in which:

Fig. 1 is a perspective view of a portable altar showing my new design;

Fig. 2 is a top plan view of the same at reduced scale; and

Fig. 3 is a side elevational view of the same at reduced scale and as seen from line 3—3 in Fig. 1.

I claim:

The ornamental design for a portable altar, as shown.

RUDOLPH T. GUDELL.
